US0D1040680S

(12) United States Design Patent (10) Patent No.: US D1,040,680 S
(45) Date of Patent: * Sep. 3, 2024

(54) JEWELRY ARTICLE

(71) Applicant: Gmeera, Eden, UT (US)

(72) Inventor: John Anderson, Hemet, CA (US)

(73) Assignee: Gmeera, Eden, UT (US)

() Term: 15 Years

(21) Appl. No.: 29/878,350

(22) Filed: Jun. 20, 2023

Related U.S. Application Data

(63) Continuation-in-part of application No. 29/794,837, filed on Jun. 15, 2021, now Pat. No. Des. 996,274.

(57) CLAIM

The ornamental design for a jewelry article, as shown and described.

DESCRIPTION

FIG. 1 is a perspective view of a jewelry article; FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

In FIGS. 1–7, the dash-dash broken lines shown illustrate portions of the jewelry article and the dot-dash broken lines illustrate bounds of the claim. The broken lines form no part of the claimed design.

1 Claim, 5 Drawing Sheets
